CLAIM

The ornamental design for an electric bicycle as shown and described.

DESCRIPTION

FIG. 1 is a top, front and left side perspective view of an electric bicycle frame showing my new design;
FIG. 2 is a bottom, rear and right side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a partial enlarged view of FIGS. 1;

FIG. 10 is a partial enlarged view of FIGS. 1;

FIG. 11 is a partial enlarged view of FIGS. 2; and,

FIG. 12 is a partial enlarged view of FIGS. 2.

The broken lines depict portions of the electric bicycle that form no part of the claimed design. The dot-dash lines in FIGS. 1-2 and 9-12 indicate the boundaries of the enlarged views and are used for annotative purpose only. They do not limit or define the scope of the claimed design.
